UNITED STATES PATENT OFFICE.

ADOLPH MYERS, OF BIRMINGHAM, COUNTY OF WARWICK, ENGLAND.

HOLDER FOR PENCILS.

SPECIFICATION forming part of Letters Patent No. 378,897, dated March 6, 1888.

Application filed September 14, 1887. Serial No. 249,642. (No model.) Patented in England May 3, 1887, No. 6,492.

To all whom it may concern:

Be it known that I, ADOLPH MYERS, a subject of the Queen of Great Britain, residing at Birmingham, Warwick county, England, have 5 invented certain new and useful Improvements in Holders for Pencils and Similar Articles, fully described and represented in the following specification and the accompanying drawings, forming a part of the same, the said improvements being embraced in English Letters Patent No. 6,492, dated May 3, 1887.

My invention has reference to improvements in pencil cases and other like cases or holders—such as pen-cases or cases for knife-blades, 15 tooth-picks, and other similar articles—in which the movement or part which holds the lead, knife-blade, tooth-pick, or other like article is caused to protrude from or to be retracted into the case or holder by pressing a cap at the upper end; and the chief object of 20 my invention is to provide a simple and inexpensive case or holder of this character in which the same movement of the pressure-cap will, by changing the position of the holder, 25 operate to both protrude and retract the lead, knife-blade, tooth-pick, or other article.

The accompanying drawings illustrate, as an example, a pencil-case constructed according to my invention.

30 In said drawings, Figures 1, 2, and 3 represent sectional views of the pencil-case and illustrate how the pencil-movement is caused to be protruded from the holder; and Figs. 4 and 5 are similar views showing how the pencil-movement can be retracted into the holder. The remaining figures represent details of the holder, Fig. 6 being a sectional elevation, Fig. 35 7 a plan view, partly in section, and Fig. 8 a cross-section, of the outer casing and inner tube; Fig. 9 a sectional elevation, Fig. 10 a plan view, and Fig. 11 a cross-section, of the pressure-cap; and Figs. 12, 13, and 14, respectively, a side elevation, partly in section, a plan view, and an end view, of the pencil-movement.

40 The pencil-movement A, which is of an ordinary form and carries the lead a, is arranged to slide to and fro in a tube, B, which I call the "inner tube," and to project from the lower end, b', thereof when in use. Around the inner tube, B, is an ordinary outer casing, C,

both being connected together at their lower ends, b'. There is an annular space between the inner tube, B, and the outer casing, C, and in this annular space is a coiled wire spring, 55 D, one end of which bears against the lower end, b', of the inner tube, B, while the other end bears against a loose ring, E, which is in contact with a pin, F, fixed to the movement A, and projecting through a slot, b², in the inner tube, B. This spring D tends to push the movement A inward into the inner tube, B. Hinged loosely to the upper end of the movement A is a weighted latch, G, which, when the movement A has been caused to protrude from the 60 inner tube, B, to its fullest extent, (see Fig. 2,) and the holder is held in a particular position, as hereinafter described, drops into engagement with a catch, b³, on the tube B, so as to hold the movement in its protruded position. The catch b³ is, in the case shown, formed 65 by a slot in the tube B, into which the latch G drops, so as to hold the movement A in its protruded position against the pressure of the spring D. Projecting from the upper end of 70 the outer casing, C, is a tubular pressure-cap, H, which fits in the annular space between the outer casing, C, and the inner tube, B. This cap H is forced outwardly by a coiled spring, I, which is interposed between the cap and 75 tube B, a pin, J, being provided on the cap, which projects inwardly into the slot b², and by engaging with the end of the slot forms a stop for preventing the cap H from being forced out too far. The pressure-cap H is herein 80 shown as made in two parts, its inner end being smaller than its outer end; but this is not material, as the cap may be of the same diameter throughout its length.

85 The operation of the holder is as follows: To cause the movement A to protrude and to remain protruded, the pencil-holder is held in a horizontal position, or nearly so, (see Fig. 1,) with the slot b³ at the lower side of the holder. The pressure-cap H is then pushed 90 inward, (see Fig. 2,) which, as its inner end is in contact with the said projecting pin F on the movement A, causes the movement to protrude from the lower end, b', of the holder, and when the movement A has been fully protruded (see Fig. 2) the free end of the weighted 95 latch G falls into the slot b³ in the inner tube, 100

B. The pressure being removed from the cap H, it will, by its spring I, be caused to regain its normal protruded position, (see Fig. 3,) leaving the movement protruded from the other end of the holder, and firmly held by the latch G, ready for use. To retract the movement A, the holder is so held that the slot b' will be at the upper side, and the pressure-cap H is pushed inwardly to its fullest extent, (see Fig. 4,) when it engages with the pin F, and, causing the movement to protrude a little farther from the case, frees the weighted latch G. As soon as this takes place, the weighted latch G will fall away from the slot b' by gravity and the spring D will be free to act, and on pressure being removed from the cap H will retract the movement A. (See Fig. 5.)

An index mark or marks may be placed upon the casing C or the cap H to indicate the position of the slot b'.

My invention can be applied to other like holders—such as pen-holders or holders for knife-blades, tooth-picks, and other similar articles—in the same manner as described with reference to a pencil-holder, the pen, 25 knife-blade, tooth-pick, or other similar article being substituted for the lead-holder in the movement A, which latter is formed to hold the article required.

30 Instead of providing the tube B with the

slot b' to receive the catch G, it may be provided with a stud or shoulder for the same purpose, and this is to be considered the equivalent of the slot.

What I claim as my invention, and desire to 35 secure by Letters Patent, is—

1. In a pencil or other similar holder, the combination, with the tube B and the movement A, reciprocating therein, of the gravitating latch G and catch b', for holding the movement in its protruded position, the spring D, acting upon the movement to retract it, and the pressure-cap H, for protruding the movement against the tension of the spring D, substantially as described. 45

2. In a pencil or other similar holder, the combination, with the movement A and the gravitating latch G, of the spring D, for retracting the movement, the tube B, the catch b', for engaging with the latch and the pressure-cap H, and the spring I, for protruding the cap, substantially as described. 50

In testimony whereof I have hereunto set my hand in the presence of two subscribing witnesses.

ADOLPH MYERS.

Witnesses:

P. HAYMARY,
JULIUS LOHMAN.
